US00D938297S

(12) **United States Design Patent** (10) **Patent No.:** **US D938,297 S**
(45) **Date of Patent:** **** Dec. 14, 2021**

(54) **PAIR OF EARRINGS**

(71) Applicant: **Harry Winston SA**, Plan-les-Ouates (CH)
(72) Inventor: **Delphine Abdourahim**, New York, NY (US)
(73) Assignee: **Harry Winston SA**, Plan-les-Ouates (CH)

(**) Term: **15 Years**

(21) Appl. No.: **29/730,886**

(22) Filed: **Apr. 9, 2020**

(30) **Foreign Application Priority Data**

Oct. 14, 2019 (WO) WIPO83433

(51) **LOC (13) Cl.** **11-01**

(52) **U.S. Cl.** **D11/42**
USPC **D11/42**

(58) **Field of Classification Search**
